CYCLOPENTANOPHENANTHRENE COMPOUNDS AND PROCESSES

Carl Djerassi, Birmingham, Mich., and Howard J. Ringold and George Rosenkranz, Mexico City, Mexico, assignors, by mesne assignments, to Syntex S. A., Mexico City, Mexico, a corporation of Mexico

No Drawing, Application July 14, 1952,
Serial No. 298,834

Claims priority, application Mexico July 26, 1951

3 Claims. (Cl. 260—239.55)

The present application relates to novel cyclopentanophenanthrene compounds and processes for producing the same. More particularly the present application relates to the production of 11-keto compounds and particularly of the sapogenin series from the corresponding 12-keto compounds.

The methods of the present invention are, therefore, capable of producing 11-keto compounds which have not heretofore been found in nature and which are valuable intermediates for the production of 11-keto adrenal hormones. As is well known, hormones of this type, such as cortisone, are extremely valuable therapeutics.

In the United States application of Carl Djerassi and George Rosenkranz, Serial No. 203,015, filed December 27, 1950, there is described a transformation of 12-keto sapogenins into the corresponding 11-keto 12-hydroxy compounds. The method of the present application relates to the transformation of the compounds thus obtained, as well as to the transformation of other 11-keto 12-hydroxy compounds into the corresponding 11,12-diketo compounds and/or the corresponding 11-enol derivatives and subsequently the removal of the 12-keto group to produce the 11-keto derivative.

A portion of the method involved for the transformation of the 11-keto 12-hydroxy compounds into the corresponding 11,12-diketo compounds and the corresponding 11-enol compounds may be illustrated by the following equation:

Although in the above equation the transformation of 22-isoallospirostan-3,12-diol-11-one to 22-isoallospirostan-3,12-diol-11-one and the corresponding enol compound $\Delta^{9(11)}$ -22-isoallospirostan-3,11-diol-12-one is shown, by way of example the reaction of the present invention above set forth may be applied to similar steroid 3,12-diol-11-keto compounds irrespective of the configuration at 3,5 and 22 of the molecule. Thus, while the above compound is a 22-isoallospirostan, the method may be applied to corresponding 22-normal spirostans. Similarly, the configuration at position 3 may be α or β . In

2

general, therefore, the above process may be applied to compounds characterized by the following general formula:

In the above formula R^1 may be alkyl, alkylene, oxy-alkyl, oxy-alkylene, keto-alkyl, keto-alkylene, carboxy-alkyl, carbalcoxy-alkyl, $CH_3-OH-OH$, $CH_3-CH-OR$, $CH_3-C=O$

When R^1 has the above values, then R^{11} is, of course, hydrogen, since the above radicals characterize those steroids with substituents at 17 only. In the case of the sapogenin series, however, both R^1 and R^{11} may be linked to either of the following radicals characterizing the 22-iso and 22-normal spirostans:

It may be noted that the method above outlined is particularly applicable to the sapogenins and is also applicable to the bile acids and compounds of the pregnane series. For example, in the bile acid series R^1 may be $COOCH_3$,

and R^{11} is hydrogen. Similarly, in the pregnane series R^{11} may be

$CH_3-CH-OH$, $CH_3-CH-OR$, or $CH_3-C=O$

and R can be an alkyl group characteristic of the lower fatty acids or aromatic acids, such as benzoic. R^{11} will, of course, be hydrogen. An example of a suitable compound in the pregnane series for this purpose is that disclosed in the form of its ester in co-pending application Serial No. 287,821, filed May 14, 1952 namely, allopregn-3 β ,12 β -diol-11,20-dione, as may be readily

understood, although the aforementioned co-pending application discloses the diacetate of this compound the free compound may be obtained by conventional methods.

In practicing the above method a suitable quantity of a 3,12-dihydroxy-11-keto steroid is dissolved in a lower fatty acid, such as glacial acetic acid or propionic acid. Bismuth oxide is then added in slight excess and the mixture is then refluxed for a period of time, such as twenty hours. Soon after the refluxing has started a black precipitated bismuth starts to form. When the reaction is complete the reaction mixture is cooled and the unreacted bismuth salts precipitated by the addition of a suitable organic solvent, such as benzene. The solution is then passed through a short column of alumina, preferably washed with ethyl acetate and the product concentrated to form a solid residue. The solid product may then be purified or it may be directly treated, as for example with pyridine and acetic anhydride, to form an enol acetate, since the product may be a mixture of the 11,12-diketo or the corresponding 11-enol-12-keto compound.

The mixture of 11,12-diketo and 11-enol-12-keto compounds may be transformed into the corresponding 11-keto compound as indicated for example by the following equation:

Although in the above equation the production of 22-isoallospirostan-3 β -ol-11-one is shown by way of illus-

tration the process is generally applicable to the steroids previously enumerated and is especially applicable to steroids of the sapogenin series so that in place of the 22-isoallospirostan compound above disclosed the corresponding 22-normal and 5-normal compounds may be utilized.

In practicing the process above set forth, the spirostan compound, as for example 22-isoallospirostan-3 β -ol-11,20-dione, in admixture with the 11-enol form, is dissolved in a suitable glycol, such as ethylene glycol, and is refluxed with hydrazine hydrate for approximately five hours. Thereafter the mixture is cooled and a suitable alkali, such as potassium hydroxide is added and the solution further heated until the temperature of the vapors reaches for example 190° C. Thereafter a reflux condenser was attached and the heating continued for approximately four hours. Upon purification the product was found to be 22-isoallospirostan-3 β -ol-11-one or other equivalent compound in the 22-normal series.

20 The 12-keto group can also be removed in accordance with the present invention by reacting the 11,12-dione in admixture with its enolic form with a suitable mercaptan, such as ethanedithiol to form the corresponding 12-mercapto. Thereafter the resultant compound may be desulfurized to produce the same type of 11-one previously

described. The following equation illustrates, by way of example, this form of the present invention:

Although in the above equation a 22-isoallo compound is shown, the above process is, of course, also applicable to the corresponding 22-normal compounds.

In practicing the step above set forth, the mixture of ketonic and enolic forms of, for example 22-isoallospirostan-3 β -ol-11,12-dione, in a suitable mercaptan, such as ethanedithiol, is cooled as for example to 0° C. and a slow stream of hydrogen chloride passed into the reaction mixture. After about two hours the flask containing the reaction mixture is placed in a vacuum desiccator for a substantial period of time to eliminate the excess hydrogen chloride. After suitable purification a crystalline mercaptol, namely the 12-cycloethylene mercaptol of 22-isoallospirostan-3 β -ol-11-one was produced. The compound thus produced could be desulfurized by refluxing the same for approximately two hours with a suitable solvent, such as ethanol and in the presence of Raney nickel. Upon purification of the resultant product the same 11-one compound resulted as that previously set forth.

The following specific examples serve to illustrate the present invention but are not intended to limit the same:

Example I

A solution of 2.0 g. of methyl 3 α ,12 β -dihydroxy-11-ketocholenate (methyl ester of Marker-Lawson's acid) in 20 cc. of acetic acid was treated with 0.88 g. (1.2 equivalents) of bismuth oxide and the mixture refluxed during four hours. After a short time a black precipitate starts separating. The solution was cooled and the unreacted bismuth salts were precipitated by the addition of 200 cc. of benzene. The solution was passed through a short column of ethyl acetate washed alumina and then concentrated to give a solid residue. It was dissolved in 20 cc. of pyridine and 10 cc. of acetic anhydride and the mixture was left overnight at room temperature and then heated on the steam bath during one hour. The cooled mixture was poured in cold dilute hydrochloric acid and extracted with chloroform, washed with water, with sodium bicarbonate solution and finally with water until neutral. Concentration of the dry chloroform solution gave crystals of methyl 3 α ,11-diacetoxyl-12-keto- $\Delta^9(11)$ -cholenate, melting point 130-132° C., λ maximum 244 m μ (log ϵ 3.97).

Example II

0.70 g. (1.2 equivalents) of bismuth oxide were added to a solution of 1.67 g. of 22-isoallospirostan-3,12-diol-1-one in 15 cc. of acetic acid and the mixture was refluxed during 20 hours. The formation of a black precipitate of bismuth started after a few minutes. After cooling, the mixture was diluted with 200 cc. of benzene and the solution was passed through a short column of ethyl acetate washed alumina and the filtrate was evaporated to dryness. The solid product obtained after grinding with methanol is a mixture of the ketone 22-isoallospirostan-11,12-dione-3-ol and the enol $\Delta^9(11)$ -22-isoallospirostan-3,11-diol-12-one. It gives a strong positive enol reaction with alcoholic ferric chloride and shows $(\alpha)_D \pm 0$.

The enol acetate was obtained by treating 0.5 of the above product with 5 cc. of acetic anhydride and 3 cc. of pyridine and heating the solution on the steam bath during 3.5 hours. The solution was poured in water and filtered after a few hours. The enol acetate thus obtained showed λ maximum 244 m μ (log ϵ 3.96). Melting point 188-192° C.

Example III

A solution of 6 g. of a mixture of 22-isoallospirostan-3 β -ol-11,12-dione and its enolic form, obtained as described in Example II, in 100 cc. of ethyleneglycol was refluxed with 10 cc. of hydrazine hydrate during 5 hours. The mixture was cooled and a solution of 4 g. of potassium

hydroxide in 5 cc. of water was added. The solution was then heated in an open flask until the temperature of the vapors reached 190° C.; a reflux condenser was attached and the heating continued four hours more. The mixture was poured in water, extracted with chloroform, washed, dried over sodium sulphate and evaporated to dryness. 4.4 g. of a solid residue was obtained which after several crystallizations from acetone-hexane gave 22-isoallospirostan-3 β -ol-11-one, melting point 224-225° C., $(\alpha)_D - 29^\circ$ (chloroform); the infrared spectrum (chloroform) showed a band of a free hydroxy group and the characteristic band of the 11-keto group at 1702 cm.⁻¹.

The mother liquors yielded a small amount of 22-isoallospirostan-3 β ,11 β -diol, melting point 202-204, formed by reduction of the 11-ketone.

Example IV

A solution of 540 mg. of the mixture of the ketonic and enolic forms of 22-isoallospirostan-3 β -ol-11,12-dione in 1.5 cc. ethanedithiol was cooled to 0°, and a slow stream of dry hydrogen chloride was passed during two hours. The flask was placed in a vacuum desiccator containing sodium hydroxide and anhydrous calcium chloride and was left overnight in order to eliminate the hydrogen chloride. The residue was taken up in ether and the ether solution was washed with dilute sodium hydroxide solution and water, dried over sodium sulphate and evaporated to dryness. The crystalline mercaptol 12-cycloethylenemercaptol of 22-isoallospirostan-3 β -ol-11-one was obtained by crystallization from hexane-ether; it gave no coloration with ferric chloride, thus indicating that the reaction was complete because the starting material gave a strong reaction (green color) with ferric chloride. The mercaptol had a melting point of 289-291° C. and on further recrystallization of 295-296° C.

The 12-cycloethylenemercaptol of 22-isoallospirostan-3 β -ol-11-one thus obtained, was refluxed during two hours with 40 cc. of ethanol and 4 g. of Raney nickel. The solution was filtered and evaporated to dryness. Upon crystallization of the residue from hexane-acetone, 22-isoallospirostan-3 β -ol-11-one was obtained with a melting point of 224-225° C., identical to the one obtained according to Example III.

We claim:

1. A new compound consisting of the 12-cycloethylenemercaptol of 22-isoallospirostan-3 β -ol-11-one having a melting point of 295-296° C.
2. In a process for the production of 22-isoallospirostan-3 β -ol-11-one, the step which comprises oxidizing 22-isoallospirostan-3 β ,12-diol-11-one with bismuth oxide in the presence of a lower fatty acid to form a mixture of 22-isoallospirostan-11,12-dione-3-ol and its enol form $\Delta^9(11)$ -22-isoallospirosten-3 β ,11-diol-12-one.
3. A process for the production of 22-isoallospirostan-3 β -ol-11-one which comprises oxidizing 22-isoallospirostan-3 β ,12-diol-11-one with bismuth oxide in the presence of a lower fatty acid to form a mixture of 22-isoallospirostan-11,12-dione-3-ol and its enol form $\Delta^9(11)$ -22-isoallospirosten-3 β ,11-diol-12-one, treating the mixture with ethanedithiol to form the 12-cycloethylenemercaptol of 22-isoallospirostan-3 β -ol-11-one and desulfurizing the mercaptol with Raney nickel.
